CLAIM

The ornamental design for a firearm, as shown and described.

DESCRIPTION

FIG. 1 is a front elevation view of a firearm;

FIG. 2 is a rear elevation view of the firearm;

FIG. 3 is a left side elevation view of a firearm with a folding butt stock extended and without accessories mounted on a front rail;

FIG. 4 is a left side elevation view of the firearm with the butt stock which is collapsed and a detachable vertical foregrip accessory, shown in phantom, mounted on the front rail;

FIG. 5 is a right side elevation view of the firearm with the folding butt stock extended and without accessories mounted on the front rail;

FIG. 6 is a right side elevation view of the firearm with the butt stock which is collapsed;

FIG. 7 is a bottom plan view of the firearm with the folding butt stock in the collapsed position;

FIG. 8 is a top plan view of the firearm with the folding butt stock in the collapsed position;

FIG. 9 is a front perspective view of the firearm with the folding butt stock in the collapsed position; and,

FIG. 10 is a rear perspective view of the firearm with the folding butt stock extended and without accessories mounted on the front rail.

The broken lines are for illustrative purposes only and form no part of the claimed design.
